UNITED STATES PATENT OFFICE.

JOHN R. LOMAS, OF NEW HAVEN, CONNECTICUT, ASSIGNOR TO BERNARD SHONINGER, OF SAME PLACE.

DESIGN FOR AN ORGAN-CASE.

Specification forming part of Design No. 7,260, dated March 24, 1874; application filed March 5, 1874.
 [Term of Patent 14 years.]

To all whom it may concern:

Be it known that I, JOHN R. LOMAS, of New Haven, in the county of New Haven and State of Connecticut, have invented a new Design for Organ-Case; and I do hereby declare the following, when taken in connection with the accompanying drawing and the letters of reference marked thereon, to be a full, clear, and exact description of the same, and which said drawing constitutes part of this specification and represents a perspective view.

This invention relates to design for the case of reed or other organs, and consists in the configuration and ornamentation of the case, as hereinafter described, and shown in the accompanying illustration.

First. The end of the case is one frame-work from the bottom to the highest point, and forward to the line of the key-board, falling back from the key-board in substantially ogee form, as shown, the frame filled with panels, as shown.

Second. The book-rack A has a raised molded edge, a raised molding crossing at the center, ornamented by a boss at the crossing, as shown.

Third. The front book-closets or abutments, one of which is shown partly open. The doors are angular or pointed at the top, with raised molded edges inclosing an ornament of tracery, as shown, and represent each a panel between two pilasters, and form the abutments for the case.

I claim as my invention—

1. The design for the ends of organ-cases, as shown and described.
2. The design for book-racks for organ-cases, as shown and described.
3. The design for the abutments or book-closets, as shown and described.

J. R. LOMAS.
